Primary Examiner—Wallace R. Burke*Assistant Examiner*—Robin V. Taylor[57] **CLAIM**

The ornamental design for a sprayer shroud, as shown and described.

DESCRIPTION

FIG. 1 is a side elevational view of a sprayer shroud showing our new ornamental design, the opposite side being a mirror image thereof;

FIG. 2 is a front elevational view thereof;

FIG. 3 is a rear elevational view thereof;

FIG. 4 is a top plan view thereof;

FIG. 5 is a bottom plan view thereof; and,

FIG. 6 is a perspective view as seen from the top and one side thereof.

The broken lines are for illustrative purposes only and form no part of the claimed design.
